(57) **CLAIM**

The ornamental design for a light fixture, as shown and described.

DESCRIPTION

FIG. 1 is a perspective view of a first embodiment of a light fixture of our design.

FIG. 2 is a side view of the light fixture of FIG. 1, the other side view being a mirror image of the side view of FIG. 2.

FIG. 3 is a front view of the light fixture of FIG. 1.

FIG. 4 is a top view of the light fixture of FIG. 1.

FIG. 5 is a bottom view of the light fixture of FIG. 1.

FIG. 6 is a perspective view of a second embodiment of a light fixture of our design.

FIG. 7 is a side view of the light fixture of FIG. 6, the other side being a mirror image of the side view of FIG. 7.

FIG. 8 is a front view of the light fixture of FIG. 6.

FIG. 9 is a top view of the light fixture of FIG. 6; and,

FIG. 10 is a bottom view of the light fixture of FIG. 6.

The rear most surface and details thereof of each embodiment of the light fixture is not part of the design.
